UNITED STATES PATENT OFFICE

ORVILLE ALDEN FOGARTY, OF MONTREAL, QUEBEC, CANADA, ASSIGNOR TO VILAS OIL
BURNERS LIMITED, OF COWANSVILLE, CANADA

ELECTRICAL SWITCH IN OIL BURNING EQUIPMENTS

Application filed January 24, 1927. Serial No. 163,136.

The invention relates to electrical switches in oil burning equipments, as described in the present specification and illustrated in the accompanying drawings that form part 5 of the same.

The invention consists essentially of the novel features of construction pointed out broadly and specifically in the claim for novelty following a description containing 10 an explanation in detail of an acceptable form of the invention.

The objects of the invention are to efficiently connect breaks in safety circuits with the least possible number of switches; to insure 15 the most efficient operation in oil burners and at the same time avoid the disastrous effects of explosions; to simplify the operations of safety mechanism with special reference to the actual running conditions 20 of the burner; to facilitate the construction and arrangement of parts; and generally to provide in oil burning mechanisms, and in fact in any device of the kind wherein there is a driving member operated through electrical connections, the greatest efficiency at 25 the least possible expense of operation and construction.

In the drawings Figure 1 is a diagrammatic view showing a stack switch and a 30 resetting switch and the wiring therebetween.

Figure 2 is a vertical sectional view of a U-shaped tube, showing its connection to the central stack tube as well as the mounting of the device.

Figure 3 is a sectional view of the casing and resetting switch, showing an elevation of the switch and operating parts.

Figure 4 is a vertical sectional view at 40 right angles to the sectional views illustrated in Figure 3.

Figure 5 is a vertical section at right angles to Figure 2.

Like numerals of reference indicate corresponding parts in the various figures.

Referring to the drawings, 10 is a U-shaped tube from which projects upwardly the extension 11 directly in the middle, this extension being turned inwardly and having 50 the stack tube 12 secured thereto, or forming

part therewith, all of these, or the stack tube alone, being made of glass that will stand a very high temperature.

The U-shaped tube at the upper end is closed by the caps 13 and 14, which contain 55 the washers or pads of fibrous material 15, ordinarily closing the air hole 16 through said caps 13 and 14. The washers or pads 15 are preferably of felt and cover the top ends of the tube 10, but being of porous 60 material, these washers or pads will permit air to pass therethrough, and through 65 openings in the caps, so long as said air is driven by the tubes at a pressure higher than atmospheric, and this air will penetrate into and through the pads, when the mercury 36 70 is raised in the legs of the tube through the expansion of air in the stack tube 12, the expansion of air in this tube being always caused by heat through the operations of 75 the furnace.

The terminal contacts 17 and 18 are adjustably screwed through the caps 13 and 14 respectively and are set in the position desired according to the pressure expected, 75 and are locked in that position by the nuts 19. Naturally these terminal contacts 17 and 18, which are rods pass through the pads 15 into contact with the mercury when the latter is forced upwardly through the 80 expansion of air in said stack tube.

The terminals 23 and 24 are fixedly secured at the upper end of the casing 21 and are wired to the contacts 17 and 18, the tube being secured by the strap 20 in a permanent position in relation to said terminals 23 and 24.

The terminals 23 and 24 are set in under the wall 25 and directly under the holes 26 and 27 respectively, these holes being ordinarily closed by the cover plate 28 held by the screw 29.

The casing 21 has an opening 31 through the back thereof, and extending through the flange 30, in which it is securely held by the packing 32, this flange being inserted in an adapter 33 preferably screwed to the stack tube 34, the flange 30 being securely held to the adapter 33 by means of the said screw 35.

It will now be seen that an unusually sensitive device is provided in this mercury electric switch for the mercury or other suitable chemical fills the bottom of the U-tube 10 and this mercury on the expansion of the air in the stack tube 12 is forced upwardly in the legs of the tube, until it reaches the contacts 17 and 18, then the electric connection is established between these two contacts and maintained constantly while the pressure remains normal.

The air bubbles, which are indicated by the numeral 36—a represent a surplusage and these are readily passed through the mercury and out through the felt pads 15 and air holes 16, thereby relieving any undue pressure, without permitting the ingress of any foreign element.

The terminals 23 and 24 are connected to the terminals 37 and 38 and the latter terminals are connected by the coil 39, so that the U-tube 10 and connecting wires form really a shunt from a starting circuit and eventually a part of an operating circuit.

The coil 39 is wound around a blind tube 40 containing acetone or spirits readily expandible, and this tube 40 extends from a Bourdon tube 42, the loose end of said Bourdon tube being pivotally secured by the connecting bars 43 and 44 to a slotted pivoted lever 45.

The chief difference in this construction now being described is that in the bar 44, there is an elongated slot 40a, through which the operating pin 47 extends, otherwise the machine may be bought on the market.

The lever mechanism is contained between two fixed plates 48 and 49 and comprises said pivoted lever 45 and the spring connection 50 drawing on said pivoted lever by means of the bars 51 secured to one arm of said lever.

The rocking bracket 52 supports the mercury tube 53, which has the two contacts 54 and 55 thereinside and projecting outwardly therefrom and connected to the terminals 56 and 57.

The bracket 52 is pivotally secured to the plates 48 and 49 and rocks with the motion of the pivoted lever 45, and as the Bourdon tube 42 is pivotally secured to the slotted pivoted lever 45 the expansion of this tube will release the mercury tube bracket and throw its nose downwardly with the result that the connection between the terminals 56 and 57 is broken. This may be restored by pressing on the spring held button 58, this button having a stem 59 engaging the cam 60 and returning the lever 45 to its original position.

In this particular invention the importance of this second mercury switch cannot be overestimated, though the actual details of its working and the description of its

parts has not to do with the invention, for it is purchased on the market as a standard machine, in fact it is a waterstat, the only difference is the use it is put to and the slotted bar which facilitates the return motion. 70

The application of these switches is not particularly described herein as this application has to do with the actual construction of the U-tube switch or stack switch, as it may be called, and the combination of 75 this stack switch with the operation of the resetting switch, for it has already been said that the details of the latter are only concerned in the operation of the safety mechanism, which forms the subject matter 80 of a pending application filed under Serial Number 118,808, consequently it will only be the broad and specific features of this U-shaped switch and its specific relation to the tilting switch that will be claimed as the 85 distinctive features of this invention.

What I claim is:—

A U-shaped tube having an upwardly projecting extension from the centre thereof, a stack tube secured to said extension, caps 90 closing the ends thereof of said U-shaped tube having lining pads of fibrous material, terminal contacts adjustably screwed through said caps and extending through said pads, a casing enclosing said tube, terminals fixedly secured at the upper end of said casing and adapted to be connected to said terminal contacts, straps securing said tube in a permanent position in relation to said casing terminals, a cover plate closing 100 in said casing terminals, said casing having a tubular rear opening through which said stack tube extends and wires from said casing terminals forming a coil encircling an acetone tube member. 105
